Jos L. Combs
Walter Morris

Henry Klanger of Philadelphia, Penn.

Letters Patent No. 3173-Dated Sept 19-1865.

Design for the Bust of Mr Lincoln.

The schedule referred to in these Letters Patent and making part of the same

To all whom it may concern:

Be it known that I, Henry Klanger, of

Philadelphia, in the County of Philadelphia, and State of Pennsylvania,

have originated and designed a new bust which may be cast in plaster,

bronze or other suitable materials, of the late Abraham Lincoln, Presi-

dent of the United States, and I hereby declare that the following is a full,

clear and exact description of the same, reference being had to the accom-

panying photographic drawings making part of this specification.

The bust consists of the head, neck and of the portion
of the shoulder and breast usually included in a bust, the whole
being of life size or a little over, although I do not confine myself
to the particular size as the same may be reduced or increased
without departure from the design or general configuration.

The bust is supported by a round pedestal or base on the upper part
of which, that is to say, on the level portion immediately above the
contracted part of the bust, is the following inscription.

2

"Abraham Lincoln."

Model and resp: dedicated to the Union

League by Henry Manger

And having thus described my design for a bust of the
late Abraham Lincoln, I claimThe design for a bust of the late Abraham Lincoln as
above described and represented in the accompanying photographic
drawings.An testimony whereof I have signed my name to this de-
claration before law subscribing witnesses

O. Newell

Theodore Parker
Jos. L. Bombs.
